A. T. LOFTSGAARDEN,
DOOR CLOSER.
APPLICATION FILED APR. 14, 1917.

1,281,181.

Patented Oct. 8, 1918.

Inventor

Albert T. Loftsgaarden

By *William W. Deane*
his Attorney

UNITED STATES PATENT OFFICE.

ALBERT T. LOFTSGAARDEN, OF POWELL, WYOMING, ASSIGNOR TO POWELL MANUFACTURING COMPANY, OF POWELL, WYOMING, A CORPORATION.

DOOR-CLOSER.

1,281,181.

Specification of Letters Patent.

Patented Oct. 8, 1918.

Original application filed March 21, 1916, Serial No. 85,583. Divided and this application filed April 14, 1917. Serial No. 162,107.

To all whom it may concern:

Be it known that I, ALBERT T. LOFTSGAARDEN, citizen of the United States, residing at Powell, in the county of Park and 5 State of Wyoming, have invented certain new and useful Improvements in Door-Closers, of which the following is a specification.

My present invention pertains to spring-10 actuated door-closing devices, and the present application is a division of my prior application filed March 21, 1916, Serial No. 85,583. The present invention contemplates the provision of a simple, strong and easily-15 applied device, calculated to quickly return a door to and retain the same in its closed position.

The invention also contemplates the provision in a door closer of improved brackets, 20 susceptible of ready connection to a door frame and door and constructed in such manner that the leverage and the tension of the retractile spring can be easily adjusted or regulated to fit the door to which 25 the closer is applied.

In the accompanying drawings which are hereby made a part hereof:

Figure 1 is a horizontal section taken through a door frame and a door and showing in plan a door closer constructed in accordance with my invention.

Fig. 2 is an enlarged detail view of one of the brackets.

Fig. 3 is a view similar to Fig. 1 and 35 showing a modification.

Referring by numeral to the drawings and more particularly to Figs. 1 and 2 thereof:

1 is the side stile of a door frame, and 40 2 is a door hinged to the stile in the ordinary, well known manner.

The stile and the door are provided on their faces with brackets 3. These brackets are substantially the same in construction 45 and therefore a detailed description of the one shown in Fig. 2 will suffice to impart a definite understanding of both. Said bracket is formed of a single piece of sheet metal and comprises spaced plates 4 having registered apertures 5 at intervals of their length, a bight 6 connecting the inner portions of said plates, and apertured ears 7 reaching at right angles to the inner ends of the plates and adapted to be opposed to

and connected with the stile 1 or door 2. 55 By virtue of the plurality of apertures 5 in the plates 4, the levers hereinafter described can be readily adjusted to regulate the tension of the spring complementary to the levers. It will also be noticed that because 60 of the construction shown and described the brackets are adapted to be easily and cheaply produced.

To the door bracket 3 a horizontally swinging arm 10 is pivotally connected. 65

A curvilinear, horizontally-swinging arm 16 is pivotally connected to the stile bracket 3. This arm 16, at an intermediate point of its length, is pivotally connected by a pintle 40 with the free end portion of the arm 10, and to the free end of said arm 16 is connected, preferably in a detachable manner, one end of a retractile spring 22.

The other end of said spring is connected with the stile 1, the connection being preferably a tension-regulating connection effected through the stile bracket 3, a loop-shaped arm 42 pivotally connected to said bracket, a bolt 26 extending through an aperture in the bight of the arm 42, and 80 a nut 28 mounted on the bolt and arranged in front of one or more coils of the spring 22.

In operation, opening of the door will be attended by outward swinging of the outer ends of both arms and the expansion of the spring, and consequently when the door is released the contraction of the spring will operate in a powerful manner to close 85 the door and yieldingly retain the same 90 in its closed position.

The modification of Fig. 3 includes brackets 3 similar to those of Fig. 1, and in addition a long horizontally-swinging arm 16^b pivoted to the stile bracket, a short arm 10^b pivoted to the door bracket and to the arm 16^b at an intermediate point in the length of the latter, and a retractile spring 22^b connected at one end to the door bracket, preferably in a detachable manner and having one or more coils at its opposite end arranged back of a nut 28^b mounted on a bolt 26^b which in turn, extends through an aperture, in the extended portion of the arm 16^b and has a kerfed head 95 back of said arm in order that the bolt can be conveniently turned to regulate the tension of the spring. 100

In the operation of the embodiment shown

in Fig. 3 the arms 10^b and 16^b are swung outwardly and the spring 22^b is stretched incidental to opening of the door, and therefore the spring operates when the door is released to strongly and quickly return the door to its closed position.

- By reference to Fig. 1, it will be noted that the bracket 3 is preferably provided with a laterally extending inner portion 4^c.
- 10 The connection between the spring 22 and the said portion 4^c is by preference a tension-regulating connection effected through a loop-shaped arm 42, preferably connected to said portion 4^c, the bolt 26 extending through an aperture in the bight of the arm 42 and the nut 28 mounted on the bolt and arranged in front of one or more coils of the spring 22 as before described.

It will be manifest from the foregoing that in each embodiment of my invention the brackets are conveniently applied to the outer sides of the stile and door; also, that the horizontally swinging arms and the retractile spring in each embodiment are arranged entirely in front of the stile and door; with the result that access may be readily gained to all of the parts for repair or adjustment purposes.

Having described my invention, what I claim and desire to secure by Letters Patent, is:

1. In a door closing device, the combination of a door frame, a door hinged thereto, a bracket on the outer side of the frame and extending laterally therefrom, a bracket on the outer side of the door and extending laterally therefrom, a horizontally-swinging

arm pivoted to the door bracket, a horizontally-swinging arm pivoted to the frame bracket and pivoted at an intermediate point 45 of its length to the first-named arm and having a portion extending beyond the latter, and a retractile spring connected with and extending between the extended portion of the second-named arm and one of the brackets; the said arms and the spring being arranged entirely in front of the frame and the door.

2. In a door closing device, the combination of a door frame, a door hinged thereto, a bracket on the outer side of the frame and extending laterally therefrom, a bracket on the outer side of the door and extending laterally therefrom, a horizontally-swinging arm pivoted to the door bracket, a horizontally-swinging curvilinear arm pivoted to the frame bracket and pivoted at an intermediate point of its length to the first-named arm and having a portion extending beyond the latter point of connection and toward the outer side of the door, and a retractile spring arranged in substantial parallel relation to the door and connected with and extending between the extended portion of the second-named arm and the frame bracket; the said arms and the spring being arranged entirely in front of the frame and the door.

In testimony whereof I affix my signature in presence of two witnesses.

ALBERT T. LOFTSGAARDEN.
